INTERCOMMUNICATING DEVICE

Luke C. Cavanaugh and Henry V. Roohk,
Cleveland, Ohio

Application November 7, 1939, Serial No. 303,267

17 Claims. (Cl. 179—100)

An object of our invention is to provide an electrical intercommunicating device which has a private ear phone as well as a loud speaker, thereby combining the convenience of a loud speaker with the privacy of an ear phone.

Another object of our invention is to provide automatic switch means between a private ear phone and a loud speaker.

Still another object of our invention is to furnish a loud speaker and a private ear phone and to provide automatic switch means governed by the ear phone which operatively selects either the loud speaker or the ear phone.

A further object of our invention is to provide a private ear phone which is enclosed substantially entirely within the housing of the intercommunicating device thereby obviating the danger of accidental displacement and breakage.

Another object of our invention is to provide a housing for an intercommunicating device which encloses the transmitter and substantially entirely encloses the ear phone thereby obviating arms and hooks which are apt to be accidentally bumped or disturbed.

Still another object of our invention is to provide a switch between a loud speaker and an ear phone and to actuate the switch by the movement of the ear phone.

Another object of our invention is to resiliently hold the private ear phone in a receptacle in the housing for the device by spring arms which actuate switches.

A further object of our invention is to provide a housing or station box for an intercommunicating device which has a receptacle in its side adapted to receive and substantially entirely enclose an ear phone.

Another object of our invention is to provide a substantially U-shaped holder with two switch means thereon and to position the holder so that the switches lie on either side of a receptacle in a housing for the device, whereby an ear phone placed in the receptacle or withdrawn therefrom will actuate both switches to control a hearing circuit and a selective circuit.

Other objects and a fuller understanding of our invention may be had from the following description and claims, taken in conjunction with the accompanying drawing, in which like parts are designated by like reference characters, and in which:

Figure 1 is an isometric view of a station box or housing for an intercommunicating device and shows a private ear phone in a receptacle in the side of the box.

Figure 2 is an enlarged view partly in cross section of a portion of the interior of the station box showing in detail the receptacle into which the private ear phone may be placed and the switches which are actuated by the ear phone.

Figure 3 is a side view of Figure 2 but not shown in cross section, and

Figure 4 is a view showing a circuit diagram which may be used in a station box using our invention.

With reference to Figures 1 and 2, our invention comprises a station box or housing 10 for an electrical intercommunicating device. The box 10 comprises a front 11, a right side 12 and 15, a top 13 as well as a left side, a back and a base. The station box 10 is substantially a complete enclosure to protect the mechanisms which are enclosed therein. The front 11 of the station box 10 is divided down the center by a brace 14 into a left opening 15 and a right opening 16. The openings 15 and 16 are covered by a fabric screen to allow sound to enter the station box and to emit therefrom. The opening 15 is adapted to receive the voice of a person who wishes 20 to converse with another station in the intercommunicating system. Transmitting means 17 are positioned behind the screened opening 15 and adapted to pick up the operator's voice and transmit it to a receiver at the other station. Behind the screened opening 16 is positioned a 25 loud speaker 18 which is adapted to receive the vocal sounds from another station in the communicating system and amplify them so that they are audible upon passing through the screened opening 16.

On the top 13 are mounted the various levers 19 and lights 20 which are necessary to operate the system.

Besides having a loud speaker our station box or housing 10 is provided with second means 30 for receiving the vocal sounds from other stations in the intercommunicating system. This second means is the private ear phone 21 which is mounted in a receptacle 22 in the station box 10. We preferably mount the private ear phone 21 in the right side 12 of the station box 10 as 35 most people are right handed. However, it is to be understood that the private ear phone 21 may be mounted in the left side for left handed persons or in the front side 11 or in the top 13. A cord 23 having wires 44 and 45 connects the private ear phone 21 with the proper circuits in the station box 10. The cord 23 is of sufficient 40 length to enable a person to place the station box 10 on a far corner of the desk at which he

is sitting and hold the private ear phone 21 to his ear.

The private ear phone 21 comprises a housing in which any of the known receiver mechanisms may be mounted. We prefer to use the crystal type as it is light in weight and gives a clear tone reproduction. Any size private ear phone may be used but for convenience we make ours about three and one-half inches long and about two and one-quarter inches in diameter. This is a handy size to hold to one's ear and also enables a person to wedge the private ear phone between his shoulder and his ear where it will stay. Both of the listener's hands are then free, enabling him to search through a file and write at the same time as he receives private directions from another station.

The receptacle 22 in which the private ear phone 21 is mounted is attached to the right side of the station box 10 by means of screws 24. When the ear phone 21 is completely inserted in the receptacle 22, the exposed end is substantially flush with the side 12 of the station box or housing. This arrangement not only gives a good appearance but also avoids accidental displacement. The receptacle 22 is substantially cup shaped and has a flared opening at the open end to facilitate the positioning of the private ear phone therein. To the other or rear end of the receptacle 22 there is attached a substantially U-shaped bracket 25 having legs 27. Any means of attaching the U-shaped bracket to the receptacle 22 may be used but we prefer nuts and bolts 26. The U-shaped bracket 25 is positioned in such a manner that the legs 27 lie along the receptacle 22 and substantially parallel therewith. Mounted on the legs 27 by means of bolts 28 are a pair of switches 29 and 34. Spring levers 30 are attached to the switches 29 and 34 by means of bolts 31. The spring levers 30 extend through slots 32 in the receptacle 22 into the space normally occupied by the private ear phone 21 where they are adapted to be actuated by the withdrawal of the private ear phone 21 and by the replacing of the ear phone into the receptacle 22. Switch buttons 33 are positioned under the spring levers 30 and are normally biased outward toward the spring levers. The removal of the private ear phone 21 from the receptacle 22 allows the spring levers 30 to move away from the switches 29 and 34 thereby releasing the pressure on the switch buttons 33 causing the switches 29 and 34 to operate. Conversely, when the private ear phone 21 is placed in the receptacle 22 it engages both spring levers 30 and causes pressure to be exerted on the switch buttons 33. Pressure on the switch buttons 33 causes the switches 29 and 34 to operate.

Beside acting as levers to operate the switches 29 and 34 the spring levers 30 function to snugly hold the private ear phone 21 in the receptacle 22. The station box 10 may be moved about and tipped but the private ear phone will not fall out of the receptacle 22.

The switch 29 operates to govern the voice receiving circuit and select either the loud speaker 18 or the private ear phone 21. Figure 4 shows a diagram of the voice circuit when the private ear phone 21 is in the receptacle 22. The voice circuit which originates at another station box in the intercommunicating system enters the station box 10 along wire 40 and may be traced as follows: from wire 40 the current flows into the switch 29 and out along wire 41 into the

loud speaker 18, and from the loud speaker 18 current flows along wires 42 and 43 back to the other station box to complete the circuit. It may be seen therefore that when the private ear phone 21 is in the receptacle 22 the loud speaker 18 is wired to operate. If the private ear phone 21 is removed from the receptacle 22 the switch 29 operates in the opposite direction as the switch button 33 is normally biased to move toward the space occupied by the private ear phone 21. The movement of the switch button 33 breaks the loud speaker circuit and establishes the following circuit through the private ear phone: the current flows along line 40 into switch 29 and out along line 44 and into the private ear phone 21 and from the private ear phone 21 current flows along lines 45 and 43 back to the other station box to complete the circuit. It may be seen therefore that when the private ear phone 21 is removed from the receptacle 22 it becomes operative and the loud speaker 18 becomes inoperative.

If a man is sitting at his desk and a signal such as the light 20 indicates that there is a call for him he can hear it by means of the loud speaker 18 without operating any switches. If, however, there is some other person in conference with him and he does not want the other person to hear his message he need only withdraw the private ear phone 21 and place it to his ear and the loud speaker 18 is automatically silenced and the call switched to the private ear phone.

The switch 34 is actuated by the normal movements of the private ear phone 21 and may be used to regulate selecting circuits in the inter-communicating system, through conductors 35 and 36.

Although we have described our invention with a certain degree of particularity, it is understood that the present disclosure has been made only by way of example and that numerous changes in the details of construction and the combination and arrangement of parts may be resorted to without departing from the spirit and the scope of the invention as hereinafter claimed.

We claim as our invention:

1. A voice transmitting and receiving station for use in a communicating system comprising in combination, an enclosure having a well, voice transmitting means in said enclosure adapted to send a voice to a second station in said communicating system, voice receiving means adapted to receive a voice from said second station, said voice receiving means comprising a loud speaker in said enclosure and a private ear phone removably mounted in said well, and switch means in said enclosure having an actuating portion extending into said well and engageable by the private ear phone to prevent operation of said loud speaker when said private ear phone is removed from said well.

2. A sound transmitting and receiving station for use in a communicating system comprising, in combination, an enclosure, a transmitter in said enclosure for sending sound, loud speaker means in said enclosure for receiving sound, removably mounted private ear phone means in said enclosure for receiving sound and switch means actuated by moving said private ear phone means into and out of said enclosure to render operable and inoperable said loud speaker means and said private ear phone means, said switch means also restraining said ear phone in said receptacle.

3. In a station housing for an intercommunicating system having receiver means and a receptacle adapted to removably receive said receiver means, the combination of switch means mounted in the station housing comprising, a substantially U-shaped holder mounted in the station housing, two switches mounted on said U-shaped holder, said U-shaped holder supporting the receptacle between said two switches, switch actuating levers mounted on said switches and extending into the said receptacle, whereby said switches are actuated by said receiver means being inserted into or removed from said receptacle and engaging or disengaging said switch actuating levers.

4. In a station housing for an intercommunicating system having receiver means and a cupped-shaped receptacle adapted to removably receive said receiver means, the combination of switch means mounted in the station housing comprising, switch actuating means connected to said switch means and extending in said cup shaped receptacle whereby it is engaged by the receiver means in said cup shaped receptacle and disengaged when said receiver is withdrawn from said cup shaped receptacle thereby actuating said switch and controlling the receiver means, said switch actuating means also restraining said receiver means in said receptacle.

5. A sound receiving device comprising, in combination, an enclosure with a stationary receptacle therein, loud speaker means in said enclosure, an ear phone adapted to be inserted substantially entirely within said stationary receptacle and switch means having resilient engaging arms and actuated by the movement of the ear phone for selectively turning said loud speaker and said ear phone on and off, said resilient engaging arms also restraining said ear phone in said receptacle.

6. A sound receiving device comprising in combination, an enclosure with a stationary receptacle therein, loud speaker means in said enclosure, switch means in said stationary receptacle and ear phone means adapted to be inserted substantially entirely within said stationary receptacle, said ear phone means actuating said switch means to turn said loud speaker and said ear phone means on and off, said switch means restraining said ear phone in said receptacle.

7. A sound receiving device comprising, in combination, an enclosure with a stationary receptacle therein, loud speaker means in said enclosure, switch means in said stationary receptacle and ear phone means adapted to be inserted in said stationary receptacle, said ear phone means actuating said switch means to operate said loud speaker and said ear phone means, said switch means restraining said ear phone in said receptacle.

8. A sound receiving device comprising, in combination, an enclosure with a stationary receptacle therein, switch means in said enclosure, spring lever means adapted to actuate said switch means and extending from said enclosure into said stationary receptacle and ear phone means governed by the switch means and adapted to be substantially entirely inserted in said stationary receptacle and adapted to engage said spring lever means to actuate said switch means, said spring lever means also restraining said ear phone means in said stationary receptacle.

9. A sound receiving device comprising in combination, an enclosure with a walled stationary receptacle therein, switch means attached to and

extending through the wall of said stationary receptacle and ear phone means governed by the switch means and adapted to be substantially entirely inserted in said stationary receptacle to actuate said switch means, said switch means restraining said ear phone in said receptacle.

10. A station for an intercommunicating system comprising, in combination, a substantially enclosed station housing having a receptacle therein, said receptacle comprising a cylinder with one end thereof closed, a transmitting device in said housing for sending communications to a second station in said system, receiving means in said housing for receiving communications from said second station; said receiving means comprising a loud speaker and a substantially cylindrical private ear phone, said private ear phone positioned substantially entirely within said receptacle and adapted to be withdrawn and placed at the operator's ear and switch means in said receptacle actuated by said private ear phone for rendering said loud speaker inoperable when said private ear phone is operable and for rendering said private ear phone inoperable when said loud speaker is operable.

11. A station for an intercommunicating system comprising, in combination, a station housing having a receptacle therein, a sound transmitter in said station housing, an ear phone adapted to be removably placed in said receptacle, a loud speaker in said station housing, two switch means in said station housing positioned on opposite sides of said receptacle, spring means attached to said two switch means and extending into said receptacle for actuating said two switch means as said ear phone is moved in or out of said receptacle, said spring means also adapted to restrain said ear phone in said receptacle, one of said switch means turning said loud speaker and said ear phone on and off and the other of said switch means being connected in the circuit of the intercommunicating system.

12. A sound transmitting and receiving station for use in a communicating system comprising, in combination, an enclosed station box having a front side enclosing means and a plurality of other side enclosing means, said front side enclosing means having opening means therein, a loud speaker positioned in the said enclosed station box and substantially behind the said opening means, a transmitter positioned in the said enclosed station box and substantially behind the said opening means, said enclosed station box having a receiver well in one of said other side enclosing means, movable private ear phone means adapted to be placed within said receiver well, switch means in said enclosed station box to selectively render operable and inoperable the said loud speaker means and the said private ear phone means, resilient switch arm means adapted to actuate said switch means, said resilient switch arm means extending into the said receiver well and adapted to be actuated upon engagement by the said private ear phone in the well means.

13. A sound transmitting and receiving station for use in a communicating system comprising, in combination, an enclosed station box having a front side enclosing means and a plurality of other side enclosing means, said front side enclosing means having two screened openings therein, a loud speaker positioned in said enclosed station box and substantially behind one of the said screened openings, a transmitter positioned in the said enclosed station box and

substantially behind the other of the said two screened openings, said enclosed station box having a substantially cylindrical receiver well in one of said other said enclosing means, cylindrical movable private ear phone means adapted to be placed substantially within said receiver well, said receiver well having a flared opening to facilitate the insertion of the private ear phone means therein, switch means in said enclosed station box to selectively render operable and inoperable the said loud speaker means and the said private ear phone means, resilient switch arm means adapted to actuate said switch means, said resilient switch arm means extending into the said receiver well and adapted to be actuated upon engagement by the said private ear phone means in the well means.

14. A sound transmitting and receiving station for use in a communicating system comprising, in combination, an enclosed station box having a front side enclosing means and a plurality of other side enclosing means, said front side enclosing means having opening means therein, a loud speaker positioned in the said enclosed station box and substantially behind the said opening means, a transmitter positioned in the said enclosed station box and substantially behind the said opening means, said enclosed station box having a receiver well in one of said other side enclosing means, movable private ear phone means adapted to be placed within said receiver well, two spaced switch means in said enclosed station box to selectively render operable and inoperable the said loud speaker means and the said private ear phone means, resilient switch arm means to actuate said switch means, said resilient switch arm means extending into the said receiver well and adapted to be actuated upon engagement by the said private ear phone means.

15. In a station housing for an intercommunicating system having receiver means and a receptacle adapted to removably receive said receiver means, the combination of switch means mounted in the station housing comprising, a substantially U-shaped holder mounted in the station housing,

two switches mounted on said U-shaped holder, said U-shaped holder supporting the receptacle between said two switches, resilient switch actuating levers mounted on said switches and extending into the said receptacle, said switches being actuated by the receiver means engaging said resilient switch actuating levers in said receptacle.

16. A sound transmitting and receiving station 10 for use in a communicating system comprising, in combination, an enclosed station box, transmitting means in said enclosed station box, loud-speaking means in said enclosed station box, said station box having a substantially cylindrical receptacle therein, said receptacle having one of its ends closed and one of its ends open and having slotted opening means in its wall, private ear phone means having a substantially cylindrical shape and adapted to slide into the said receptacle through the open end thereof, switch means in said enclosed station box to selectively render operable and inoperable the said loud-speaking means and the said private ear phone means, resilient switch arm means adapted to 15 actuate said switch means, said resilient switch arm means extending through the said slotted opening means and adapted to be actuated upon engagement by said private ear phone means, said private ear phone means substantially closing the said open end of the receptacle.

17. In a station housing for an intercommunicating system having receiver means and a receptacle adapted to removably receive said receiver means, the combination of switch means mounted in the station housing comprising, spaced mounting means, spaced switch means mounted on said spaced mounting means, said spaced mounting means supporting the receptacle between said two switches, resilient switch actuating levers adapted to actuate said switches and arranged to extend into said receptacle, said switches being actuated by the receiver means engaging said resilient switch actuating levers in said receptacle.
